UNITED STATES PATENT OFFICE.

JACOB M. WOODLING, OF MOUNT JEWETT, PENNSYLVANIA.

TANNER'S BEAM.

SPECIFICATION forming part of Letters Patent No. 613,483, dated November 1, 1898.

Application filed June 14, 1898. Serial No. 683,422. (No model.)

To all whom it may concern:

Be it known that I, JACOB M. WOODLING, a citizen of the United States of America, residing at Mount Jewett, in the county of Mc-
5 Kean and State of Pennsylvania, have invented certain new and useful Improvements in Tanners' Beams, of which the following is a specification, reference being had therein to the accompanying drawings.

10 This invention relates to improvements in tanners' tools, and particularly to that class known as "beams," for fleshing, unhairing, and dressing skins, the object of the invention being to produce such a beam formed of
15 iron, steel, brass, copper, or any other metal that will withstand the attack of the tools employed in treatment of skins. Where wooden beams are employed, it has been found that the surface speedily becomes cut and even
20 necessitating frequent change to insure satisfactory action.

It is the object of this invention, therefore, to produce a metallic beam the surface of which will be uniform at all times.

25 Furthermore, the object of the invention is to produce such a beam which will be sufficiently rigid to sustain the weight and pressure incident to its use, yet making it light and easily handled by the operator.

30 A further object of the invention is the provision of novel means whereby the marking of skins is obviated. Furthermore, I contemplate the production of a beam which will possess advantages in points of simplicity,
35 efficiency, and durability, making it at the same time inexpensive.

With the above and other objects in view the invention consists in the details of construction and in the arrangement of parts to
40 be hereinafter more fully set forth and specifically claimed.

In describing the invention in detail reference will be had to the accompanying drawings, forming part of this specification, where-
45 in like characters of reference denote corresponding parts in the several views, in which—

Figure 1 is a face view of my improved tanner's beam. Fig. 2 is a plan view looking at the under side thereof; and Fig. 3 is a sec-

tional view taken on the line 3 3 of Fig. 2, 50 looking in the direction of the arrow.

In the drawings, *a* denotes the body of the beam proper, consisting of a metallic plate curved in cross-section, as shown in Fig. 3, and the degree of curve may be varied to suit 55 the individual opinions of the users or manufacturers. On the under side of the plate I provide braces 2, consisting of metallic strips having their ends bent at approximately right angles with relation to the strip proper, and 60 the ends so bent are secured to the under surface of the body by means of bolts 4, the heads of which are countersunk into and flush with the upper surface of the body. Nuts 5 are run on the bolts and retain the braces in place. 65 As will be apparent, these braces will prevent the body from sagging or collapsing when the hide is supported thereon and will, furthermore, sustain the pressure of the operator.

On the under side of the beam, at the edge 70 thereof, on one end, I provide a wooden rim 6, by the use of which marking of the hide is prevented. This rim may be secured in place in any convenient manner; but in practice I prefer to employ rivets, although I may provide screw-holes extending part way into the under surface, whereby the said rim may be removably attached.

It will be understood in view of the foregoing that various changes may be made in 80 the proportions and other details of construction without departing from the spirit of the invention.

Having now fully described my device, what I claim, and desire to secure by Letters Patent, is—

A tanner's beam consisting of a curved metallic plate, braces having their ends bent at approximately right angles and secured to the under side of the plate, and a rim removably 90 attached at the edge of the beam, as and for the purpose described.

In testimony whereof I affix my signature in the presence of two witnesses.

JACOB M. WOODLING.
